ABSTRACT

A TR-limiter apparatus includes a pre-TR unit for response to RF energy of a predetermined minimum level. The unit includes a gas-filled vial mounted between a resonant cavity and a slot for coupling RF energy below the predetermined level to the cavity and for reflecting RF energy above the predetermined level. A resiliently biased member urges the gas-filled vial firmly against a retaining surface of a housing to maintain the vial at the inner end of a coupling slot through which the RF energy is supplied. In this manner, the recovery time of the pre-TR unit is minimized and the resonant frequency of the cavity is stabilized despite thermal cycling of the vial and the housing in the operation of the TR-limiter apparatus.

MEANS FOR RETAINING GAS-FILLED VIAL IN PRE-TR UNIT

BACKGROUND OF THE INVENTION

1. Field of the Invention

The present invention relates to TR-limiter apparatus, and more particularly to a pre-TR unit connected in series with a TR tube, a diode limiter, and a return signal receiver for limiting the power applied to the receiver.

In the field of radar, for example, TR-limiter apparatus is used to prevent output pulses from a transmitter from being received directly by the return signal receiver. Depending upon the power level of the output pulses, the TR-limiter apparatus may include a diode-limiter for response to low average power pulses, a TR tube for response to medium average power pulses, and a pre-TR unit for response to high average power pulses.

The recovery time of the TR tube or the pre-TR unit is the time between the end of an output pulse and the instant at which the TR tube or pre-TR unit is in condition to pass a return signal to the receiver. Obviously, the recovery time should be as short as possible so that the entire return signal from each output pulse is applied to the receiver. In a TR tube or other gas-filled device in which the gas ionizes in response to an output pulse, the recovery time is the time required for the gas to de-ionize once the output pulse stops.

2. Description of the Prior Art

In the past, pre-TR units located between the transmitter and the receiver have been made from vacuum-tight enclosures containing gas that ionizes in response to each output pulse and thus protects the receiver. To simplify the pre-TR units and permit use of less expensive castings, the gas has, in the past, been contained in a thin-walled vial fabricated from quartz, for example, or another material having a low dielectric constant and the ability to withstand operating temperatures up to 100° C, for example. The outer cylindrical surface of the vial has been ground to a uniform diameter and the vial received in an accurately machined cylindrical aperture provided in a housing. A wall having a thickness of about 0.025 inches extends between a retaining surface of the aperture and an outside surface of the housing. A coupling slot extends from the outside surface through the wall and intersects the aperture. A cavity is provided in the housing on the side of the aperture opposite from the coupling slot and intersects a central portion of the aperture. The cavity terminates half way across the aperture and has a height that exceeds the diameter of the aperture such that a shoulder is formed on each side of the aperture.

In the past, the vial has been secured in the aperture by upsetting each shoulder to provide a lip extending partially around the vial. Also, a mass of fibrous quartz has been inserted in each end of the aperture to prevent axial movement of the vial in the aperture.

The above-described structure of the pre-TR unit has been the source of a number of problems. In particular, the quartz vial adjacent to the coupling slot changes the resonant frequency of the cavity. It has been found that this resonant frequency varies according to the intimacy of the contact of the vial with the inner end of the coupling slot. Because the diameter of the aperture cannot practically be machined with exact accuracy, a 1 to 3 mil gap may exist between the inner end of the

coupling slot and the outer surface of the vial. To eliminate this gap, the upset lip must urge the vial against the coupling slot of the aperture. However, it is difficult to form the lips in this manner and the upsetting tool often breaks the vial. Further, most of the force of the lips on the vial is applied in a direction perpendicular to rather than toward the coupling slot which tends to crack the vial without retaining it in the aperture. Also, because the aperture diameter increases more than the vial diameter during operation, the lips permit the vial to become loose and move away from the inner end of the coupling slot such that the resonant frequency varies to an uncontrolled extent.

Of equal importance, studies of these problems indicate that such movement of the vial also increases the recovery time of the pre-TR unit. In particular, movement of the vial away from the inner end of the coupling slot decreases the density of the ionization (or plasma discharge) in the vial, and as the density decreases, the time required for the gas to deionize increases.

SUMMARY OF THE INVENTION

The present invention avoids the disadvantages of the prior technique for holding the vial in the aperture of the pre-TR unit while increasing the range of energy of output signals to which the pre-TR section is responsive. In particular, without increasing the requirements of accuracy for the fabrication of the vial aperture or the outer diameter of the vial, the present invention includes facilities for firmly holding the vial against the portion of the vial aperture that is adjacent to the coupling slot. In greater detail, such facilities are effective to hold the vial firmly against such portion of the vial aperture during operation of the pre-TR unit even though the vial and the aperture expand different amounts in response to temperature variations accompanying operation of the pre-TR unit. As a result, the recovery time of the pre-TR unit of the present invention is stabilized and variations in the resonant frequency slot are minimized. Further, breakage of vials during the process of securing the vial in the aperture has been reduced to insignificant proportions.

An object of this invention is to provide a new and improved TR-limiter apparatus.

Another object of the present invention resides in minimizing the recovery time of a gas-filled vial mounted in a pre-TR unit of a TR-Limiter apparatus.

A further object of the present invention is to provide facilities in a pre-TR unit for firmly mounting a gas-filled vial adjacent to a coupling slot through which RF energy is admitted.

A still further object of the present invention resides in an aperture provided in a housing of a pre-TR unit for receiving a gas-filled vial that is engaged by a resiliently biased retainer having a vial engaging end section conforming to the shape of the vial for holding the vial firmly in position adjacent an interior end of a slot through which RF energy is coupled.

With these and other objects in view, the present invention contemplates the use of a gas-filled vial in a pre-TR unit for protecting a radar return signal receiver from high energy output (or radar) pulses. The gas-filled vial is mounted in a first aperture extending parallel to and closely spaced from an end surface of a housing of the pre-TR unit. A slot for coupling the output pulses into the aperture extends through a portion

of the wall between the first aperture and the end surface. A second aperture provided in the housing extends parallel to the end surface and intersects the first aperture. A retaining member slidably received in the second aperture is urged against the vial by a resilient member. The end of the retaining member that engages the vial is shaped to conform to the shape of the outer surface of the vial. The retaining member is dimensioned and the second aperture is located relative to the first aperture such that the retaining member exerts a resultant force on the vial that includes a force component in the direction of the coupling slot and perpendicular to the longitudinal axis of the first aperture so that the vial is held firmly in the aperture notwithstanding size variations of the vial and dimensional variations of the aperture which occur during high temperature operation of the pre-TR unit. The length of the retaining member and the shape of the vial engaging end thereof are designed to minimize the electrical effect of the retaining member on the operation of the pre-TR unit while enabling the retaining member to maintain enough component force on the vial to firmly hold the vial in the aperture.

BRIEF DESCRIPTION OF THE DRAWINGS

Other objects and an understanding of the present invention may be obtained upon reference to the following description of a preferred embodiment thereof when taken in conjunction with the appended drawings in which:

FIG. 1 is an outline drawing of a TR limiter apparatus including a pre-TR unit connected to a transmitter for preventing radar output pulses from being conducted to a receiver;

FIG. 2 is an end view of the pre-TR unit located between the transmitter and a TR tube illustrating a quartz, gas-filled vial secured in place by a resiliently biased retaining member;

FIG. 3 is a cross-sectional view of the pre-TR unit taken along line 3-3 in FIG. 2 showing the retaining member urging the gas-filled vial to the left against a retaining wall of an aperture so that the vial is urged into intimate contact with an inner end of a coupling slot; and

FIG. 4 is a graph illustrating the relationship between the angle at which the retaining member applies a resultant force to the vial and the length of the retaining member.

DESCRIPTION OF THE PREFERRED EMBODIMENT

Referring now to the drawings, a TR-limiter apparatus 10 constructed according to the principles of the present invention is shown in FIG. 1 including a transmitter 12 for generating a series of output pulses 14, such as those used for radar purposes. In such applications, a target (not shown) reflects the output pulses 14 and generates a return signal 16 which is conducted by a pre-TR unit 18, a TR tube 20, and a diode-limiter 22 to a receiver 24. The pre-TR unit 18, the TR tube 20, and the diode-limiter 22 are also effective to isolate the receiver 24 from the output pulses 14 so that the amount of power fed to the receiver 24 is limited to the power level for which the receiver is designed.

Referring now to FIG. 2, the pre-TR unit 18 is shown in detail including a housing 26 which may be fabricated from a casting, such as of aluminum. As shown

in FIGS. 2 and 3, the housing 26 has a generally rectangular cross-section and is provided with spaced end surfaces 27 and 28. The surface 27 is mounted against a waveguide (not shown) of the transmitter 12, whereas the surface 28 is mounted against the TR tube 20. A first, generally rectangular aperture 29 is provided in the housing 26 and extends (in the direction of an axial line 30) from the surface 28 for defining a resonant cavity 31. The cavity 31 is provided with side walls 32, an end wall 33 and respective top and bottom walls 34 and 36.

A second or vial aperture 37 is provided in the housing 26 and extends generally perpendicular to the line 30 along an axis 38. The second aperture 37 is shown having a cylindrical cross-section, although other cross-sections would be suitable. The second aperture 37 intersects the end wall 33 of the cavity 31 such that a portion 41 of the second aperture 37 that is co-extensive with the cavity 31 is provided with a generally semi-circular cross-section for defining a retaining surface 42.

The housing 26 is further provided with a third aperture 43 extending generally parallel to the surfaces 27 and 28 and intersecting the bottom wall 36 of the cavity 31 adjacent to the retaining surface 42. In addition, a slot 44 is provided in the housing 26 extending from the surface 27 through a wall 46 that extends between the end surface 27 and the retaining surface 42 for permitting the pulses 14 and the signal 16 to enter the second aperture 37.

As shown in FIGS. 2 and 3, a vial 47 having an outer surface 48 shaped to conform to the shape of the second aperture 37 is received in the housing 26 with the surface 48 touching the retaining surface 42. The vial 47 may suitably be fabricated from quartz although materials other than quartz may be selected if they have a suitably low dielectric constant and a similar ability to withstand the relatively high temperatures encountered during the operation of the TR limiter apparatus 10. The vial 47 is sealed for enclosing a gas, such as chlorine, which becomes ionized to form a plasma discharge in response to a pre-determined amount of energy from an output pulse 14. When the gas is ionized, an output pulse 14 will be reflected to isolate the receiver 24 from the output pulse 14.

Although the diameter of the second aperture 37 is carefully machined so as to maintain accurate tolerances, it is generally not practical to machine the second aperture 37 such that the diameter thereof is substantially identical to that of the outer surface 48 of the vial 47 which is ground to a relatively constant diameter. As a result, if the vial 47 is not held in place, it is usually free to move to a limited extent, such as 1-3 mils, relative to the retaining surface 42.

As noted above, prior techniques for securing the vial 47 against the retaining surface 42 of the second aperture 37 have resulted in variations of the resonant frequency of the cavity 31 in an uncontrolled amount. In addition, it has been found that certain movement of the vial 47 permitted by such prior methods results in a measurable increase in the time required for the gas in the vial to de-ionize after the output pulse 14 stops. In particular, the recovery time of prior pre-TR units is significantly increased when the vial moves away from an inner end 51 of the coupling slot 44.

The pre-TR unit 18 of the present invention avoids the problems associated with such prior techniques by

providing in the third aperture 43 a slidable retaining member 52 having a first end 53 provided with a reduced diameter section 54, an intermediate section 56 having a diameter slightly less than that of the third aperture 43 and a third, inner end section 57 having a surface 58 thereon having a shape that conforms to the shape of the outer surface 48 of the vial 47. As shown in FIG. 3, when the vial 47 has a circular cross-section, the surface 58 of the member 52 that engages the vial has an arcuate contour conforming to that of the outer surface of the vial. The first end 53 of the member 52 is shown surrounded by a resilient member 61, such as a coil spring, which extends further outwardly in the third aperture 43 to a set screw 63 which is received in a threaded section 64 of the third aperture 43. The position of the set screw 63 in the third aperture 43 is adjusted to compress the coil spring 61 so as to urge the member 52 into engagement with the outer surface of the vial 47. The resultant force (shown by arrow 65) applied by the retaining member 52 against the vial 47 has a retaining or horizontal component (shown by arrow 66) extending to the left as viewed in FIG. 3. This retaining force component 66 is significant enough (such as 2 ounces) to maintain the vial firmly in contact with the retaining surface 42 so that a section 67 of the outer surface of the vial 47 is maintained adjacent to the inner end 51 of the coupling slot 44. In this manner, the vial 47 is held in a pre-determined location such that once the resonant frequency of the cavity 31 has been adjusted (by means of a tuning rod 68 shown in FIG. 3) the resonant frequency of the cavity remains constant.

It may be appreciated that the coefficients of thermal expansion of the quartz vial 47 and the aluminum housing 26 are different. Thus, the diameter of the aperture 37 and that of the vial 47 do not change at the same rate upon heating during operation of the pre-TR unit 18. The resiliency of the coil spring 61 compensates for differences in the size of the second aperture 37 and the vial 47 caused by heating or by machining tolerances by maintaining the section 67 of the vial 47 in contact with the retaining surface 42. In this manner, the resonant frequency of the cavity 31 is stabilized and the gas discharge within the vial (that results from a pre-determined amount of energy coupled through the coupling slot 44) is of constant density so that the recovery time for the pre-TR unit 18 does not vary.

Referring now to FIG. 4, there is shown a graph indicating the relationship between the length of the retaining member 52 as a function of the force angle or angle at which the resultant force 65 is applied by the retaining member 52 to the outer surface 48 of the vial 47. Superimposed on the graph is an outline of the retaining member 52 viewed as in FIG. 3 and illustrating side surfaces 71 and 72 of the retaining member 52 along with the arcuate surface 58 which conforms to the shape of the outer surface 48 of the vial 47. Dashed lines 73, 74, 76, and 77 represent various end surfaces of the member 52 and thus illustrate varying lengths which the member 52 may have. For purposes of convenience, the lines 73, 74, 76, and 77 are shown measured downwardly from a horizontal line 78 passing through the centerline of the vial 47. Thus, the line 73 representing the longest length of the retaining member 52 is indicated as being 0.05 inches from center line 78 and the end line 74 is indicated as being 0.07 inches from the center line 78.

Referring again to FIG. 4, the graph also shows a series of lines 81, 82, 83, and 84 which pass through the intersection of center lines 78 and 86. The intersection of the lines 78 and 86 defines the longitudinal axis 38 of the vial 47. The angle A between the horizontal center line 78 and the lines 81, 82, 83, and 84 indicates the angle of the resultant force 65 applied by the various retaining members 52 on the vial for the lengths indicated by respective lines 73, 74, 76, and 77.

In general, the force angle lines 81-84 indicate that as the length of the retaining member 52 is decreased, the horizontal (or leftward) retaining component of force 66 decreases, thus there is less force to retain the vial 47 against the retaining surface 42. In addition, it may be understood that for a given diameter retaining member, as the length of the retaining member 52 decreases, the area of contact between the retaining member 52 and the vial 47 decreases such that for a given resultant force 65 applied to the vial, the pressure on the vial 47 increases. Also, it may be appreciated that the more the retaining member 52 extends into the cavity 31, the greater the reactive effect of the member 52 on the resonant frequency of the cavity 31. Because the ideal length of the retaining member from a reactive standpoint would result in a negligibly small retaining force and a substantial increase in the pressure applied to the vial 47, the length of the retaining member 52 is selected so as to provide an adequate retaining force 66, and a relatively large contact area while being short enough to have a reactive effect on the resonant frequency that can be compensated for by adjustment of the tuning screw 68. In a particular embodiment of the present invention, the length of the retaining member 52 as measured from the line 78 was 0.07 inches.

Tests conducted with the pre-TR unit 18 of the present invention confirm the stabilization of the resonant frequency of the cavity 31 and the minimization of the recovery time of the pre-TR unit. However, an additional unexpected result of the use of the retaining member 52 of the present invention is that the level of RF power required to ionize the gas in the vial 47 is significantly reduced, apparently because the retaining member (when fabricated from aluminum, for example,) acts as a high potential point. The high potential is thought to cause the gas to ionize at a lower level of incident of RF energy, thus providing an increased range of protection to the TR tube 20.

It may be understood that the principles of the present invention may be used by those in the art in embodiments other than that disclosed above. For example, a pair of retaining members 52 mounted on opposite sides of the vial 47 may be used to apply increased components of retaining force 66 to the vial 47 for added security in holding the vial against the retaining surface 42.

What is claimed is:

1. Apparatus for limiting the electrical power of a transmitted signal supplied to a receiver, comprising: housing means for defining a cavity, said housing being provided with a first surface and a first aperture intersecting said cavity, said aperture including a retaining surface extending adjacent to said first surface so as to define a wall bounded by said first surface and said retaining surface, said housing means being provided with a slot having an inner end adjacent to said aperture for coupling said transmitted signal to said aperture;

gas discharge means received in said aperture in said housing means;
means slidably mounted in said housing means and movable into said cavity for engagement with said gas discharge means; and means for urging said 5 slideable means into engagement with said gas discharge means to press said gas discharge means firmly against said retaining surface and adjacent to said inner end of said coupling slot.

2. The apparatus of claim 1, in which: 10 said gas discharge means is a gas-filled vial, said slideable means is received in a second aperture provided in the housing means on the side of the first aperture opposite to said retaining surface so that said slideable means is effective to press said 15 vial against said retaining surface and said slideable means is provided with a surface having a shape conforming to the shape of the outer surface of said vial for reducing the pressure applied to the outer surface of said vial.

3. The apparatus of claim 1, in which: 20 said cavity and first and second apertures are mutually perpendicular; and, said gas discharge means is a gas-filled vial; and said slideable means engages one side of said vial for 25 exerting a force on said vial, said force having a component directed toward said coupling slot for maintaining the side of said vial opposite to said one side against said retaining surface of said aperture.

4. A pre-TR device adapted to limit the power of a signal applied to a receiver, comprising: 30 a housing having a first surface and a cavity, said housing including a slot extending through said surface toward said cavity for coupling a signal having 35 a maximum selected power level to said cavity, said

housing being provided with a first aperture extending along said surface and intersecting and extending between both said coupling slot and said cavity;

a gas-filled vial received in said aperture for limiting the power level of the signal received by said cavity from said coupling slot to said selected power level; a member having a first end provided with a shape conforming to the shape of the outer surface of said vial for contacting said vial; and means for resiliently urging said member against said vial to maintain said vial against the wall of said first aperture adjacent to said coupling slot.

5. The apparatus of claim 4, in which: said housing is further provided with a second aperture intersecting said cavity, said member is slidably received in said second aperture for movement into engagement with the outer surface of said vial, and said first end of said member is designed to extend a minimum distance into said cavity and to exert a force on said vial at least a component of which is in the direction of said coupling slot for maintaining said vial against said wall of said aperture.

6. The apparatus of claim 4, in which: said cavity and said first aperture intersect so that at said intersection said first aperture has a generally semi-circular cross-section, said vial is mounted in said aperture and extends into said cavity at said intersection; and said urging means presses said retaining member into engagement with the portion of the vial that extends into the cavity so that the vial is maintained against said wall of said aperture adjacent said coupling slot.
